UNITED STATES PATENT OFFICE

LAWRENCE E. LAWSON, OF CHICAGO, ILLINOIS, ASSIGNOR TO SAFETY MINING COMPANY, OF CHICAGO, ILLINOIS, A CORPORATION

BLASTING CARTRIDGE AND METHOD AND MEANS FOR OPERATING THE SAME

Application filed October 7, 1929. Serial No. 398,074.

The present invention is concerned with a blasting cartridge and a method and means for operating the same. However, the invention is concerned more particularly with an operating method and means which may be adapted to use with any known form of blasting device.

An object of the invention is to provide an entirely safe method and means for effecting the discharge of blasting devices.

A further object is to provide a remote control actuating device for blasting devices without the use of electricity.

A still further object is to provide a positive actuation for blasting devices, with adequate protection against accidental discharge.

Specifically, it is an object of the invention to provide a fluid actuated means for effecting the discharge of blasting devices.

Another of the more specific objects of the invention is to provide a fluid actuated means for effecting the discharge of gas charged blasting cartridges of the general type hereinafter described.

The principles of the invention are illustrated in the accompanying drawings, but it should be understood that they may be incorporated in a variety of structures differing from that herein shown.

In the drawings,

Figure 1 is a view in longitudinal section of a portion of a blasting cartridge embodying my invention.

Figure 2 is a transverse section along line 2-2 of Figure 1.

Figure 3 is an enlarged detail view in section, showing the charging valve.

Figure 4 is a sectional view taken along line 4-4 of Figure 1, and

Figure 5 is a detail view of the bayonet slot connection between the heater and heater support.

The cartridge with which the present invention is illustrated is of that type wherein a charge of compressed gas is employed as the blasting medium. Structurally the cartridge consists of a metallic container 1 in which is formed a gas chamber 2. An end of the gas chamber is open but is adapted to be closed by means of a rupturable disc fixed in posi-

tion by a discharge cap. The particular form of the discharge mechanism is not herein shown since it forms no part of the present invention.

Leading into the gas chamber 2 is a charging passage 3 which communicates with a transversely arranged pocket 4 formed in the end of the body 1. This pocket is provided with screw threads for the reception of a correspondingly threaded plug 6. A suitable packing gland 7 is secured to the plug and has engagement with the wall of the pocket in order to seal against the escape of gas from the chamber 4. A valve stem 8 is threaded centrally through the plug 6 and is provided on its end with a substantially conical valve 9 which is designed to cooperate with the passage 3 for the purpose of controlling communication between chamber 4 and gas chamber 2. An angularly directed passage 10 extends from the surface of the shell body inwardly to the chamber 4. At its outer extremity this passage 10 is enlarged to form a seat 11 adapted to receive a charging nozzle.

The end of the cartridge body is provided with screw threads for cooperation with similar threads formed internally of a cap member 12. This cap member is of hollow construction and is elongated in an axial direction to provide a cylinder 13 with which a passage 14 in the end of the cap communicates. Located within the cylinder 13 is a piston 15 secured to one end of a piston rod 16. The end of the cartridge body is provided with axial bore 17 through which the piston rod 16 is adapted to slide. A suitable stuffing box 18 is provided to prevent the escape of gas from the chamber 2 around the piston rod. Thus, it will be appreciated that fluid pressure introduced through the port 14 will serve to move the piston in an axial direction, thereby projecting the piston rod into the gas chamber 2.

In order to prevent accidental movement of the piston rod 16 and also to provide for the rapid and forceful actuation thereof it is desirable to restrain the piston rod against movement until a predetermined pressure is exerted thereon through the medium of the fluid pressure and the piston. For this pur-

pose, the piston rod is provided with a transverse opening 19 through which extends a frangible pin 20. This pin is adapted to be inserted through an aperture 21 in one wall of the cap and to have its opposite end seated in a pocket 22 located at a diametrically opposite point in the cap wall. A pivoted cover plate 23 serves to secure the pin 20 in position. The end of the cartridge body 1 is recessed as indicated at 24 to provide a pocket into which the sheared portion of the pin 20 may pass when the piston and piston rod are moved axially. The outer edge of this pocket serves as an anvil or shear ring against which the pin may be forced by the pressure of the compressed fluid in order to shear the pin at two definite points.

Within the gas chamber 2 there is provided a heater support 25 which is screw threaded in the end of the cartridge as indicated at 26. A tubular heater unit 27 may be positioned within the support 25 and may be secured against axial movement with respect thereto by means of a pin 28 carried by the heater and bayonet slots 29 formed in the support. The end of the heater may be provided with a suitable form of detonating cap with which the end 30 of the piston rod 16 is adapted to cooperate to energize the heater.

In view of the foregoing description it will be appreciated that the present invention consists broadly of a fluid pressure operated striker rod designed to set off a detonating cap within a blasting cartridge. It will be understood, of course, that suitable piping may be connected with the cylinder 13 at the inlet opening 14 and that the operating fluid pressure may be generated and controlled from a remote point. Specifically, the invention contemplates a fluid pressure operated striker rod in combination with a means for preventing accidental displacement thereof and also holding the same against movement until a predetermined pressure is exerted thereon in order that the action of the striker rod may be rapid and forceful. The invention therefore provides an entirely safe method of effecting the discharge of blasting cartridges without the aid of electricity or other dangerous forms of power.

I claim:

1. A blasting cartridge comprising a substantially cylindrical casing having a gas chamber formed therein, a heater support mounted in said casing, a heater unit positioned within said support with an end thereof of adjacent one end wall of the chamber, a striker rod extending through said end wall in proximity to the end of said heater, a cylinder associated with said cartridge, a piston within said cylinder and having connection with a source of fluid pressure, and a frangible pin associated with said striker rod for retaining the same in inoperative position

until a predetermined pressure is exerted thereon.

2. A blasting cartridge comprising a substantially cylindrical body having a gas chamber formed therein, an end of said cartridge having a transversely arranged pocket therein with a passage placing said pocket in communication with said gas chamber and a second passage leading from the exterior of said cartridge into said pocket, and a valve in said pocket for controlling communication between the pocket and the first said passage.

Signed at Chicago, Illinois, this 2nd day of October, 1929.

LAWRENCE E. LAWSON.
